UNITED STATES PATENT OFFICE.

WENZEL J. SCHERF, OF MANITOWOC, WISCONSIN.

FUMIGATING-CONTAINER.

1,351,263.

Specification of Letters Patent. Patented Aug. 31, 1920.

Application filed June 3, 1919. Serial No. 301,536.

To all whom it may concern:

Be it known that I, WENZEL J. SCHERF, a citizen of the United States, residing at Manitowoc, in the county of Manitowoc and State of Wisconsin, have invented a new and useful Fumigating-Container, of which the following is a specification.

The object of my invention is to provide a fumigating container of novel construction, which may be placed in suit cases, trunks and tool boxes for the purpose of fumigation. I attain the objects of my invention by the device shown in the accompanying drawings, in which—

15 Figure 1 is a longitudinal sectional view of the device;

Fig. 2 is a top plan of same; and

Fig. 3 is a detail perspective view of members 14, 15, 16 and 17.

20 Like numerals designate like parts in each of the views.

Referring to the drawings, I provide a container 1 of suitable material, preferably aluminum, and which may be of any suitable shape, either round as shown or shaped like a watch. In the upper portion of container 1 is a filling opening 2 covered by a cap 3. I provide container 1 with an elongated neck 4 extending well into the body 25 of the container. Mounted on the lower portion of neck 4 is a fine screen 13. Spaced above screen 13, I provide a suitable wire ring 15 having a loop 14 extending into the center of the ring and slidably engaging the vertical extending wire 17, the upper portion 30 of which is bent to form the upper ring 14, as shown in Fig. 3. A suitable spring 16 is attached to the ring 15 and tends to draw it toward ring 14. Positioned 35 between rings 14 and 15, I provide suitable

absorbent material 19, preferably twisted yarn, as illustrated in Fig. 1. Removably mounted on the neck 4, I provide a cap 5 having a suitable top 6 provided with perforations 7. Rotatably mounted on the top 45 portion 6 of cap 5 by means of pivot 8, I provide a cover 9, which is provided with perforations 10 positioned to align with perforations 7 when the cover is adjusted for allowing the fumes of the fumigating liquid within container 1 to escape. Members 6 and 9 may be either flat as shown, or preferably of acorn shape; and member 9 is provided with any suitable means for rotating same, such as the small tongues 11. I may 50 provide a cork 12 which may be inserted in the neck 4 of the container when it is not being used. The considerable amount of absorbent material contained between members 14 and 15 in the extended neck 4 prevents 55 any leakage of the fumigating liquid in case the device is overturned.

What I claim is:—

A fumigating container having a body portion, means for admitting a liquid into 65 the container, an extended neck member projecting a considerable distance into the body of the container, a screen mounted in the lower portion of said neck member, spaced wire rings, one of the rings having an integrally formed wire extending longitudinally of the neck of the container, the other ring having a looped portion slidably engaging said longitudinally extending wire, 70 a spring operatively connected to the two 75 rings and arranged to draw one of the rings toward the other, and a relatively large amount of absorbent material positioned between the two rings.

WENZEL J. SCHERF.
